United States Patent Office

Des. 204,354
Patented Apr. 5, 1966

204,354

CIGARETTE SNUFFER

Milton R. Revzin, 727 Delaware Ave., Youngstown, Ohio

Filed Aug. 19, 1965, Ser. No. 86,642

Term of patent 14 years

(Cl. D85—2)

FIG. 1

FIGURE 2 is a perspective view showing the bottom, the back, and the other end thereof.

I claim:

The ornamental design for a cigarette snuffer, as shown.
